[57] CLAIM

The ornamental design for a wrapping table, as shown
and described.

DESCRIPTION

FIG. 1 is a front isometric view of a wrapping table
showing my new design;
FIG. 2 is a front elevational view thereof;
FIG. 3 is a rear elevational view thereof;
FIG. 4 is a top plan view thereof;
FIG. 5 is a bottom plan view thereof; and
FIG. 6 is a left side elevational view thereof, the right
side being a mirror image of the left side.
